Primary Examiner — Sheryl Lane*Assistant Examiner* — Mark T. Philipp(74) *Attorney, Agent, or Firm* — D'Ambrosio & Menon, PLLC; Usha Menon(57) **CLAIM**

The ornamental design for a roller valve rod guide, as shown and described.

DESCRIPTION

FIG. 1 is a top view of our new design for a roller valve rod guide;

FIG. 2 is a bottom view thereof;

FIG. 3 is a right view thereof;

FIG. 4 is a front view thereof;

FIG. 5 is a sectional view thereof taken along the line 5-5 in FIG. 4;

FIG. 6 is a perspective view thereof;

FIG. 7 is a back view thereof; and,

FIG. 8 is a left view thereof.

1 Claim, 8 Drawing Sheets(56)
